UNITED STATES PATENT OFFICE.

ROBERT M. CRAIG, OF WILKINSBURG, PENNSYLVANIA.

METALLIC DENTURE BACKING.

Application filed June 27, 1919. Serial No. 307,104.

To all whom it may concern:

Be it known that I, ROBERT MEADE CRAIG, a citizen of the United States, residing at Wilkinsburg, in the county of Allegheny, and State of Pennsylvania, have invented a certain new and useful Improvement in Metallic Denture Backings, whereof the following is a specification, reference being had to the accompanying drawing.

10 My improvement relates to a metallic backing for a porcelain tooth facing, which may be utilized in a plate, bridge, or other form of denture, and of the class contemplated in Letters Patent 12,753 reissued to me February 18, 1908.

Letters Patent of the United States 1,221,420, granted to me April 3, 1917, with claims for such a backing comprising a pair of opposed and oppositely counterpart members, spaced and arranged to embrace the porcelain body between them and united by a fusible element between them. I found it convenient to make those members of cast metal, and such construction is advantageous in that such members of a single size may be used to form metallic backings of different sizes, by interposing more or less of the fusible element between them. However, that

30 method of manufacture requires a great deal of time and skilled labor, and it is the object of my present invention to provide a backing structure which is susceptible of quantity production with the minimum amount of labor, by a method and means which form the subject matter of other applications for Letters Patent of the United States copending herewith. Said

method is claimed in application Serial 305,421 filed June 19, 1919, and said means include metal drawing dies claimed in application Serial 305,422, filed June 19, 1919, and pressing mechanism claimed in application Serial 308,590 filed July 3, 1919.

45 In accordance with that method, a primarily plane strip of sheet gold, of uniform thickness, is drawn through suitable dies to form an I-bar, having opposite faces of substantially cylindiform curvature, so that the opposite longitudinal edges of said bar are about twice as thick as the middle portion thereof, throughout its length. Said bar is then divided to form a plurality of backing blanks, by similar successive punching operations each of which produces a single blank, of approx-

imately rhombic configuration, the shorter axis of which coincides with the longitudinal axis of said bar. Each of said blanks is then pressed, in suitable dies, so as to turn its thick edges upward, in substantially parallel relation, so that it is U shaped in cross section, considered transversely with respect to the original bar, although arched at its intermediate portion in the direction of the length of said bar, to form the metallic denture backing which I desire to claim herein.

50 My improved backing, formed as above described, differs from that shown in my Letters Patent 1,221,420 aforesaid not only in that it is formed of a single piece of metal, instead of being formed of three pieces; but also in that the web thereof intermediate of its side flanges is of uniform cross section throughout its length and thinner at its medial longitudinal axis than at its opposite edges. It may be observed that such differences connote a material saving in gold, as the result of employment of my present invention, in comparison with the 55 form of backing shown in said Letters Patent 1,221,420, in which the intermediate web was not only of irregular cross section throughout its length but of considerable thickness to engage the fusible element.

60 In other words; my present invention is advantageous, as compared with that shown in said Letters Patent, not only in providing a metallic backing of the specific class contemplated at great saving of skilled 65 labor and consequent cost of manufacture; but with a substantial saving in the amount of precious metal required for a given backing.

70 My invention includes the various novel 75 features of construction and arrangement herein specified and claimed.

In said drawing; Fig. I is a perspective view of a portion of the I-bar from which the metallic backing blanks are formed.

Fig. II is a perspective view of a single 80 backing blank punched from said I-bar.

Fig. III is a perspective view of the U-shaped backing pressed from said blank.

Fig. IV is a central longitudinal sectional 85 view of said backing; showing the uniform thickness and arched configuration of its central web.

Fig. V is a plan view of said backing embodied in a denture representing a bicuspid tooth, showing that, although substantially 90 U-shaped in cross section, its flanges are

closer together at their free edges than at their junctions with said web so as to form an undercut recess to receive the porcelain tooth facing of said denture.

5 Fig. VI is a front elevation of said bicuspid denture.

Fig. VII is a left side elevation of said bicuspid denture.

Fig. VIII is a rear elevation of said bicuspid denture.

Referring to Fig. I; the I-bar aforesaid has its opposite faces substantially cylindrically curved throughout its length, so as to form a thin web 1 with opposite thick longitudinal edges 2, of the same transverse cross section, throughout its length. Such a bar is preferably formed of gold, but may be formed of any other suitable metal or alloy.

Referring to Fig. II; it may be observed that the backing blank 3, which is conveniently formed from said bar by a punching operation, is of approximately rhombic outline, having its axis 4 corresponding with the longitudinal axis of said bar. It is to be noted that the shape of said blank is such that the major portion of its area is formed of the thinner portions of said bar; only a fraction of said area being formed of the thickest, edge portions, of said bar.

30 Referring to Fig. III; it may be observed that the substantially U-shaped metallic backing, formed from said blank 3, has opposite side flanges formed by the thick edges 2 aforesaid bent so that they converge both 35 from the bottom toward the top, and from the thin intermediate web 1 toward the observer. Although said side flanges merge into said web directly at the upper edge of the latter; they merge into said web above 40 the lower edge of the latter so as to leave a downwardly projecting portion 5, which, as hereinafter described, forms a locking flange for engagement with the porcelain facing to prevent the accidental escape of the latter from said backing; although said flange may be returned to the 45 position shown in Figs. III and IV to permit said facing to be removed at any time.

Fig. IV shows the arched configuration to 50 which the thin web of said backing is bent from the straight initial form of the bar shown in Fig. I, and also shows the uniform thickness of said web throughout the length of said backing.

55 Referring to Figs. V to VIII inclusive; the porcelain body comprises the anterior portion 7 and the posterior portion 8 in unitary relation. Said anterior portion forms a facing which may be of any desired size, 60 representing a natural tooth, and said posterior portion forms a dovetail 9 whereby said body is supported in and engaged by said metallic backing 10, which may form part of a plate, bridge, or other denture. As 65 indicated by the dotted lines in Figs. V, VI

and VIII; said dovetail 9 is wedge shaped in two directions at right angles to each other, its side faces converging both from its occlusal end 11 to its gingival end 12 and from its lingual side 13 to its labial or buccal side 14, where it merges into the anterior portion 7 of said body; said converging surfaces being symmetrically disposed with respect to the central vertical plane of the porcelain body. Said posterior dovetail portion 9 is also converged and concavely curved longitudinally in its lingual face, from its gingival end toward its occlusal end, as best shown at 9 in Fig. VII. Said posterior portion 9 of said porcelain body being thus converged in three directions, as above described, is fitted in the correspondingly shaped recess in said metallic backing 10, the exterior contour 14 of which resembles that of the tooth imitated by the anterior portion 7 of said porcelain body.

It is to be noted that the construction and arrangement above described are such that the strains to which the denture is normally subjected, viz, pressure in a direction from its occlusal or incisal end toward its gingival end, and transversely from its lingual to its labial side, merely serve to more firmly seat said porcelain body in its backing 10. Although there is no normal strain upon the denture tending to remove said porcelain body from its metallic backing in the direction from its gingival end to its occlusal end, it may be manually slid and removed in that direction, without removing the backing from its setting, whenever it is desired to remove the porcelain body. Therefore, although it is unnecessary to provide any special means for preventing such sliding movement in addition to the frictional engagement between said body and its backing, they may be cemented in connection with each other, and I prefer to provide said backing 10 with the unitary locking flange 5 which, when bent as indicated in dotted lines in Fig. IV and in full lines in Fig. VII, normally prevents said porcelain body from thus sliding; so that it is necessary to straighten said flange 5 to the position shown in full lines in Fig. IV and in dotted lines in Fig. VII, to remove said body. Said locking flange 5 may be rebent to engage the porcelain body when it is replaced in said backing 10.

Of course, my present invention also differs from that claimed in said Letters Patent 1,221,420, in that it is necessary to have dies of respectively different sizes corresponding with different sizes of natural teeth, to form the blanks shown in Fig. II and bend them as exemplified in Fig. III. However, the cost of such dies is negligible as compared with the great saving in cost of manufacture above contemplated. A single bar, such as shown in Fig. I, may be of

such size and proportions that it may be used for all sizes of blanks required. All sizes of porcelain bodies for a given tooth may be conveniently recessed alike, to receive the side flanges of metallic backings such as above described; so that the dies for forming the different sizes of the latter may be all of one pattern, for a given tooth, except that they are of respectively different widths.

Therefore, I do not desire to limit myself to the precise details of construction and arrangement herein set forth, as it is obvious that various modifications may be made therein without departing from the essential features of my invention, as defined in the appended claims.

I claim:

1. A metallic denture backing comprising a single piece of pressed sheet metal of uni-

form thickness in parallel planes but of greater thickness at its opposite edges than intermediate thereof, and having a bendable locking flange intermediate of said edges.

2. A metallic denture backing comprising a single piece of pressed sheet metal of uniform thickness in parallel planes but of greater thickness at its opposite edges than intermediate thereof.

3. A metallic denture backing having a thin middle part and thickened projections at opposite edges extending to said middle part only.

In testimony whereof, I have hereunto signed my name at Wilkinsburg, Pennsylvania, this sixth day of November, 1918.

ROBERT M. CRAIG.
